UNITED STATES PATENT OFFICE.

FERDINAND H. LANGE, JR., OF WILKES-BARRE, PENNSYLVANIA.

SLIDING-DOOR HANGER.

No. 815,182.

Specification of Letters Patent.

Patented March 13, 1906.

Application filed August 31, 1904. Serial No. 222,878.

To all whom it may concern:

Be it known that I, FERDINAND H. LANGE, Jr., a citizen of the United States, residing at Wilkes-Barre, in the county of Luzerne and State of Pennsylvania, have invented a new and useful Sliding-Door Hanger, of which the following is a specification.

The invention relates to improvements in sliding-door hangers.

10 The object of the present invention is to improve the construction of sliding-door hangers and to provide an exceedingly simple and inexpensive one of great strength and durability designed for use in houses, barns, and elsewhere and capable of being readily applied to a door and adjusted to fit the same.

15 A further object of the invention is to provide a sliding-door hanger of this character which will be noiseless and which will be effectually prevented from jumping the track.

20 With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be 25 resorted to without departing from the spirit or sacrificing any of the advantages of the invention.

25 In the drawings, Figure 1 is a side elevation of a sliding-door hanger constructed in accordance with this invention and shown applied to a door. Fig. 2 is a plan view of the same. Fig. 3 is a transverse sectional view on the line 3 3 of Fig. 1. Fig. 4 is a detail view of one of the blocks which forms the 30 seats for the shaft or axle. Fig. 5 is a detail view of the shaft or axle. Fig. 6 is a detail sectional view taken on the line 6 6 of Fig. 2.

35 Like numerals of reference designate corresponding parts in all the figures of the drawings.

40 1 designates a horizontal track consisting of a round pipe or tube provided in its upper face with a longitudinal slot 2 and having its ends fitted in sockets 3 of disks or plates 4. 45 The sockets are formed by annular flanges and are preferably interiorly threaded to receive the threaded ends 5 of the pipe or tube. The disks or plates are perforated for the reception of screws or other suitable fastening 50 devices for securing them to the opposite walls or supports. Instead of threading the

ends of the pipe or tube the latter may be secured within the annular flanges of the disks or plates by any other suitable means. In the accompanying drawings the invention is 60 applied to a sliding door 6; but it may be readily applied to a pair of sliding doors, as will be readily understood, and when a pair of pipes or tubes are employed their adjacent ends may be connected and supported by a 65 hanger of any desired construction. Also instead of employing disks or plates 4 and sockets 3 any other suitable means may be used for supporting the ends of the track.

70 The slot 2, which extends along the track a distance to permit the necessary movement of the door, receives a central annular flange 7 of a wheel 8, which is provided with a grooved periphery presenting concave faces 75 9 to the adjacent portions of the pipe or tube and conforming to the configuration of the same. The central annular flange extends through the top of the track and preferably bears against the inner face of the bottom of the same and assists in sustaining the weight 80 of the door. The flange 7 divides the groove of the wheel or roller into two separate spaces, and it projects beyond the peripheries of the side walls of the groove. The wheel is provided with a central opening 10, through 85 which passes a shaft or axle 11, having slotted or bifurcated ends 12 for the reception of hanger-rods 13, extending from the shaft or axle to the door, as clearly shown in Figs. 1 and 2 of the drawings. The shaft or axle extends from opposite sides of the wheel, which is arranged between washers 14, held against the wheel by pins or keys 15, as indicated in Fig. 3 of the drawings.

90 In order to reduce the friction to a minimum, the wheel is provided at its center with an annular chamber 16, forming a ball-race for the reception of antifriction-balls 17, and in order to enable the parts to be readily assembled the wheel is preferably divided longitudinally at 18 in the plane of one of the side faces of the central annular flange 7 to form two sections, as clearly shown in Fig. 3. The sections may be secured together in any desired manner after the parts have been 100 assembled.

105 The hanger-rods 13, which are arranged at a slight inclination and which have their upper ends fitted in the slots or bifurcations of the ends of the shaft or axle, are held against lateral movement by pins or keys 19, which 110 pierce the ends of the axle beyond the rods

and which are secured in position after the rods have been placed in the slots. The upper ends of the rods are threaded for the reception of nuts 20, and blocks 21 are interposed between the nuts and the axle or shaft. The blocks, which are perforated for the reception of the rods, are provided with grooves 22 to form seats for the axle or shaft. Instead of providing threads and nuts any other suitable means may be employed for retaining the blocks on the upper ends of the rods.

The hanger-rods, which are located at opposite sides of the track, extend in opposite directions from the axle or shaft, and their outer ends are bent at a slight angle and are arranged horizontally in sleeves or eyes 23 of attachment-plates 24, which are secured to the upper edge of the door, adjacent to the side edges thereof, as clearly shown in Fig. 2. The lower or outer ends of the rods may be provided with nuts 25, or any other suitable means may be employed for securing them to the attachment-plates. The attachment-plates are detachably mounted on the upper edge of the door, each plate being provided with a depending boss 26, centrally arranged and having a threaded bore 27 therethrough. Screws 28, passing through the plate, engage the door. A keeper-roller 29, bearing against the under side of the track, is journaled to and between spaced upstanding ears 30, carried by the upper end of a stem 31, that is threaded through the bore of the boss 26 and preferably extends downwardly into a socket 32, formed in the upper edge of the door. Thus adjustable connections are provided between the outer ends of the hanger-rods 13 and the opposite upper corners of the door. The peripheral grooved wheel, which presents oppositely concavely curved faces to the round track, conforms to the configuration of the same and is practically noiseless. In order to limit the movement of the door, the track is provided with a stop 33, consisting of a cushion or buffer of rubber or other suitable material, mounted on a shoe 34, which extends upward from a plate 35. The plate 35 is secured by a screw or other suitable fastening device to the track, and the shoe and the buffer are curved to conform to the configuration of the wheel and preferably extend to a point above the center of the same. The stop may be mounted at any desired point and is adapted to prevent the hanger from being injured.

It will be seen that the sliding-door hanger is exceedingly simple and inexpensive in construction, that it possesses great strength and durability, and that as the door is suspended from the supporting-wheel by the hanger-rods, which are located at opposite sides of the track, the hanger is effectually prevented from leaving the latter. In view of the fact that a single supporting-wheel is employed, it will be evident that there is a tendency of

the door to swing upon the axis of rotation of said wheel. This is prevented by the rollers 29, and said door may be hung properly, so as to avoid any binding action or undue frictional engagement. The wheel is provided with bearing portions at both the top and bottom of the track, and there is no liability of it jumping the same.

Having thus fully described my invention, what I claim as new, and desire to secure by Letters Patent, is—

1. A sliding - door hanger, comprising a hollow track provided at the top with a slot, a supporting-wheel having a periphery conforming to the configuration of the track and provided with a projecting flange arranged to run in the slot, and means for suspending a door from the supporting-wheel.

2. A sliding-door hanger, comprising a hollow track provided at the top with a slot, a supporting-wheel having a periphery conforming to the configuration of the track and provided with a projecting flange extending through the slot to the bottom of the track and arranged to run on the same, and means for suspending a door from the supporting-wheel.

3. A sliding - door hanger, comprising a track, a supporting-wheel, a door, and hanger-rods located at opposite sides of the track and extending from the wheel to the outer portions of the door.

4. A sliding - door hanger, comprising a track, a supporting-wheel, an axle having slots, rods arranged in the slots, blocks mounted on the rods and forming seats for the axle, and means for connecting the rods with a door.

5. The combination with a door, of a supporting-track, a roller running on the track, oppositely-extending hanger-rods connected to the roller at opposite sides of the track, and plates attached to the rods and secured to the door at opposite sides of the center thereof.

6. The combination with a door, of a supporting-track, a roller running on the track, oppositely-extending hanger-rods connected to the roller and secured to the door, and rollers adjustably mounted on the door at opposite sides of the center thereof and engaging the under side of the track.

7. The combination with a door, of a supporting-track, a fixed axle, a roller journaled on the fixed axle and arranged on the track, hanger-rods connected to the axle on opposite sides of the roller, plates secured to the door and connected to the said rods, and rollers adjustably mounted on the said plates and engaging the under side of the track at opposite sides of the center of the door.

8. The combination with a door, of a track, a roller running on the track, oppositely-extending hanger - rods connected with the roller, plates secured to the door and fastened

to the rods, said plates having bosses, stems threaded in the bosses, and rollers carried by the stems and engaging the track on opposite sides of the center of the door.

5 9. In a door-hanger, a roller having a peripheral groove and provided with a central annular flange dividing the groove into two spaces.

10. In a door - hanger, a roller having a grooved periphery and provided with a central flange dividing the groove into two spaces and projecting beyond the peripheries of the side walls of the groove.

11. In a door - hanger, a roller having a grooved periphery and provided with a central flange dividing the groove into two spaces, said roller being divided longitudinally to form two sections and the flange being carried by one of the sections. 15

In testimony that I claim the foregoing as 20 my own I have hereto affixed my signature in the presence of two witnesses:
